Blakeslee, Davis, & Beecher,
Knitting Machine.

No. 80,853.

Patented Aug. 11, 1868.

United States Patent Office.

CHARLES W. BLAKESLEE AND ANTHONY G. DAVIS, OF WATERTOWN, AND
EBENEZER B. BEECHER, OF WESTVILLE, CONNECTICUT.

Letters Patent No. 80,853, dated August 11, 1868.

IMPROVEMENT IN KNITTING-MACHINES.

The Schedule referred to in these Letters Patent and making part of the same.

TO ALL WHOM IT MAY CONCERN:

Be it known that we, CHARLES W. BLAKESLEE and ANTHONY G. DAVIS, of Watertown, in the State of Connecticut, and EBENEZER B. BEECHER, of Westville, in the same State, have invented certain Improvements in Knitting-Machines; and we do hereby declare that the following, taken in connection with the drawings which accompany and form part of this specification, is a description of our invention sufficient to enable those skilled in the art to practise it.

Our improvements relate to a novel construction and mode of mounting and operating a travelling thread-carrying arm; to a novel means for varying its length of circuit of travel, for widening and narrowing, without arresting its movements in a continuous course; and to other details hereinafter mentioned; and they are peculiarly applicable to that class of machines having two parallel rows of reciprocating needles and a single thread-guide or eye, which delivers yarn first to one and then to the other, in order to knit tubular goods.

In machines of this general construction, the thread or yarn-deliverer has usually been made to traverse to and fro on a bar located above the space between the rows of needles; but in the application filed by us, April 14, 1868, and now pending in the Patent Office, the thread-deliverer, whilst continuously traversing around the machine with the cam which operated the needles, became at each end of the machine detached from the devices which operated it.

Our present invention consists in the combination, with a thread-carrying arm or bar, of a swivelling support, which is arranged to slide upon the arm, to admit of its being held in proper place, whilst going around the end of the machine.

Also, in the combination, with such arm, of an adjustable rod or rods, for arresting the range of travel of the yarn-delivering eye, and causing the arm to turn around the end of the machine.

Also, in a means for automatically locking such sliding support preparatory to the delivery of the yarn along the straight line of needles, and automatically releasing it at the end of the line.

Also, in a peculiar construction of a thread-delivering tube or eye, by which it is enabled to perform the duty of serving as a pin or pivoting centre for the sliding arm, as well as the duty of supplying yarn to both rows of needles.

Also, to other minor features hereinafter described.

In the drawings accompanying and making part of this specification—

Figure 1 represents my improved devices applied to a machine, the outline only of the latter being shown, and

Figure 2 represents a longitudinal section detached from the machine, of the yarn-carrying slide and its support, and a portion of the cop or spool-bearing rod.

A represents the body of a knitting-machine, arranged for two parallel rows of needles, the latter not being shown. B is a driving-crank. C, a bevelled-cog wheel, and D a corresponding wheel, for imparting motion to the endless linked chain E, which supports and carries the needle-actuating cams F E, the latter sliding in a way, G. H is an arm or bracket-support, which travels coincidently with the cam, and may be secured thereto. I is a straight rod, fitted in a swivelling sliding sleeve or support, K, which is so mounted upon the arm H as freely to turn upon its centre when required. L is a spring-catch, secured to the bracket or arm H, and which, by the force of the spring, engages with a notch, M, on the under side of rod I, as shown in fig. 2, in order to hold the latter in proper position for the delivery of the yarn along the straight line of needles; but the detention by this spring is light enough to permit its hold to be overcome when the pin N, upon the arm I, has, at the end of its traverse, become locked, as hereinafter described, in the nick or opening O, cut in the inner end of the narrowing and widening bars or pieces P. The pin N is made somewhat flattened or oblong in its cross-section, at that portion which is to enter the nick O; and the latter is made, preferably, somewhat flaring at its mouth, that the pin may enter it without fail, and circular beyond its

mouth, to permit the pin to turn therein without escaping from it during the act of turning. The pin N is made hollow, that it may receive the yarn, and thus also perform the duty of thread-carrier and deliverer; the pin is also curved, as shown, so as to deliver the yarn to that row of needles which is on the side of the machine upon which the cam is for the time being moved.

A supplemental eye for the yarn may be made if desired, as at Q. When this is used, it would deliver the yarn to the opposite row of needles, and the hollow pin in such case would not be supplied with yarn, but only perform its duty of governing the motions of sleeve K. The rods P pass through and are sustained by socket-heads R, which screw into the body of the framework, and they are held in any desired position therein, according as the fabric to be made requires to be widened or narrowed, by detaining-pins S, which pass through holes in the socket-heads R, as shown, and also through any one of a series of equidistant holes in the rods P. T is a standard, for holding the cop or bobbin, and it is rigidly affixed to the rod I, and travels with it. This standard is so formed as to hold the bobbin inverted, as shown, and so that its delivering-end is about in line with and in close proximity to the eye of the guide which delivers the yarn directly to the needles.

A great advantage resulting from this arrangement is, that all intermediate guide-eyes or wires to direct the course of the thread are dispensed with; and a still more important advantage is that it avoids any useless slack or let-off of the yarn, and consequently dispenses with the necessity of employment of any sort of take-up devices, which tend to encumber a machine, as well as to vary the even character of the work by any variation or irregularity in their action.

The parts being adjusted in the position shown in the drawings, and the machine put in motion by the turning of the crank, which may be either by hand or by power, the cam, bracket, rod I, yarn-delivering guide, and bobbin are carried along simultaneously, the yarn being at the same time delivered to one row of needles; and when the yarn-guide or carrier has reached the last needle which is to be supplied with yarn, the pin N enters the notch O, in the end of rod P, and is arrested and prevented from going farther. The arm H, however, continues its course around the end of the machine, and in so doing unlocks the slide from its spring-detent, and draws it back upon the bar or rod I of the yarn-carrier.

During this latter movement, and in which the pin or tube N is within the slot, it will be perceived that, by reason of its flattened or oblong form, it cannot, after it has commenced to turn, become disengaged from the circular part of the slot, nor escape from the mouth of the same, until it has turned a half circle, at which stage its edge is again presented towards the mouth, and it is again ready to emerge from it in the same manner that it entered it.

The same action precisely takes place at the other end of the machine, after the thread-carrier has traversed along and delivered its yarn to the other row of needles: at the commencement of each traverse, in a straight line, the spring L being in position relatively to notch M to lock the bar I to the slide K, until it needs again to be released to run back on the rod.

During the whole operation of knitting, the cop or bobbin of yarn, travelling as it does with the yarn-delivering guide, and in close proximity to it, lets off no slack beyond what is wanted for immediate use, and hence no take-up devices are needed. The arrangement of the cop of yarn, with its tip pointing downwards, and with its axis nearly in a line coinciding with the eye of the yarn-deliverer, also insures an even draught of the thread at all times, and dispenses with any additional or supplemental guiding-eyes usually employed in knitting-machines.

It is evident that the rows of needles may be placed farther apart than is shown in the drawing. In such case, a needle or two, or the requisite number of needles to make a regular continuous course, could be arranged at the end of the rows, or in the slides at the end of the machine, in any suitable way, and the pin N, acting also as a yarn-deliverer, would then deliver yarn to these needles also.

I claim the combination, with a thread-carrying arm or bar, of a swivelling support, substantially as described, which is arranged to slide upon said arm to admit of its being held in proper place whilst going around the end of the machine.

Also, the combination, with such arm and a swivelling support, of an adjustable rod or rods, for arresting the range of travel of the yarn-delivering eye, and causing the arm to turn around the end of the machine.

Also, the combination, with such thread-carrying arm, of an automatic locking and releasing-device, operating substantially as and for the purpose set forth.

Also, the combination, with such thread-carrying arm, of a tubular eye, constructed to serve as a pin or pivoting centre for the thread-carrying arm, as well as to perform its duty of supplying yarn to all the needles which are brought into action for knitting.

CHARLES W. BLAKESLEE,
ANTHONY G. DAVIS,
EBENEZER B. BEECHER.
